UNITED STATES PATENT OFFICE.

JAMES E. BROWN AND CHAUNCEY B. BROWN, OF BRADFORD,
PENNSYLVANIA.

VEHICLE-BODY.

SPECIFICATION forming part of Letters Patent No. 699,488, dated May 6, 1902.

Application filed April 10, 1901. Serial No. 55,170. (No model.)

To all whom it may concern:

Be it known that we, JAMES E. BROWN and CHAUNCEY B. BROWN, citizens of the United States, and residents of Bradford, in the county 5 of McKean and State of Pennsylvania, have invented a new and Improved Vehicle-Body, of which the following is a full, clear, and exact description.

This invention has for its object to provide 10 an improved construction for a vehicle-body which greatly strengthens the body where the parts are secured together and dispenses with the use of screws and short plugs usually employed for the attachment of parts of the body 15 and that frequently become loose or produce defacement of the finished exterior of the body.

The invention consists in the novel construction and combination of parts, as is here- 20 inafter described, and defined in the appended claim.

Reference is to be had to the accompanying drawings, forming a part of this specification, in which similar characters of reference indi- 25 cate corresponding parts in all the figures.

Figure 1 is a plan view of a vehicle-body having its parts joined together by the improved means. Fig. 2 is an enlarged trans- 30 verse sectional view of details taken, substan- tially, on the line 2 2 in Fig. 1. Fig. 3 is an enlarged sectional plan view of a corner por- 35 tion of the body, showing details of the im- provement. Fig. 4 is a transverse sectional view substantially on the line 4 4 in Fig. 3; and Fig. 5 is a sectional plan view taken, sub- 40 substantially, on the line 5 5 in Fig. 2.

In the drawings, which show the details of the improvement, 6 indicates the bottom frame of a body having a rectangular form 45 and suitably elongated, this shape being the popular design for the body portion of a buggy or other light passenger-vehicle. The sides 7 of the body are either plain exteriorly or paneled, as may be preferred, and at suitable intervals between their ends are provided with like keys 8. Each key 8 is formed of hard wood, parallel on its sides and grooved on its edges, preferably in V shape, as indicated in Figs. 1 and 3.

50 The keys 8 are of a length equal to the thickness of the frame 6 and are each tightly fitted

within similar channels a, formed oppositely in pairs in the inner surface of a side 7 and an adjacent outer edge of the frame 6, said channels being undercut in their side walls, 55 which adapts two channels when located directly opposite each other to receive the grooved edges of one of the keys 8.

It will be seen that if a proper number of the keys 8, formed as described, are driven 60 within opposite and mating channels a, formed in the outer edges of the frame 6 and in the sides 7 at and near their lower edges, the sides at their lower edges will be very firmly affixed upon the outer edges of the 65 body-frame 6 without the use of screws and filling-plugs, that are liable to deface the exterior surface of the finished sides 7.

It is to be understood that the keys 8 may be secured in place by means of glue or other 70 cement or be simply held in place by their frictional contact with the surfaces of the channels they occupy.

The ends 9 of the body are also held upon the outer edges of the ends of the frame 6, 75 intermediately of the extremities of said ends, by means of keys 8, which are grooved on their edges and bedded in opposite undercut channels a, as already described with regard to the sides 7. 80

To secure the corners of the sides and end walls in a neat and very substantial manner upon the frame 6, we have provided a novel device for each corner, comprising the following details: A post 10 is provided for each 85 corner of the body and may be substantially rectangular in cross-section, thus being adapted to fit against the inner surfaces of a side 7 and end wall 9 at and near a respective corner of the body. Upon a corner of the 90 post 10, nearest the adjacent ends of the walls 7 and 9, an integral corner-block 10^a is formed thereon, which is triangular in cross-section. The web b, that joins the corner of each post 10 to an adjacent side of a corner-block 10^a, 95 is of sufficient thickness to insure strength therefor, and the web occupies an opening formed to receive it by cutting away the adjacent ends of the side and end walls of the body, each at an angle of forty-five degrees, 100 so that one side of the triangular corner-block upon which the web is formed at its

center will be adapted to have close engagement with the beveled ends *c* of the side and end walls 7 9, as clearly shown in Figs. 1 and 3. Each corner-post 10 is secured to the end 5 wall and side wall of the vehicle-body by two keys 10^b, that are firmly secured in vertical slots *b'*, formed in the post and body walls, as shown in Figs. 1 and 3.

The location of the triangular corner-blocks

- 10^a at respective corners of the rectangular vehicle-body, as described, provides right-angled corners therefor, the sides of each of said corner-blocks that are exterior being in the same plane with a respective side or end 15 wall of the body and, in effect, becoming parts thereof, as represented in Figs. 1 and 3.

At a proper point on the sides 7 a novel seat-frame is secured to extend transversely of the body, and, as represented in Fig. 2,

- 20 which shows the construction of the seat-frame where it is attached to one side wall of the body, said features of the improvement comprise the following details: The cross-bars 11 (see Fig. 1) extend transversely of the 25 vehicle-body and are held spaced apart in parallel planes by the attachment thereto of a seat-board 12. Upon a respective end of each cross-bar 11 a leg 13 is secured, either by means of a slot-and-tenon connection or in 30 any other manner that may be preferred.

The length of the cross-bars 11 is such as adapts the legs 13 to depend at the inner sides of the body side walls 7, and in the latter a vertical groove *d*, having undercut sides, is 35 formed opposite each leg, whereon a mating dovetailed tongue *d'* is formed that is slid endwise into the groove, which engagement of parts affords a secure and very reliable connection of the legs with the sides 7.

- 40 A rectangular notch *d*² is formed in the exterior edge of the frame 6 opposite each leg 13, and a tenon *e*, which is formed on the lower end portion of a respective leg, engages within an appropriate notch *d*² and is held 45 therein by any preferred means.

The bottom frame 6 of the vehicle-body is rabbeded on the upper inner edge for the reception of a floor or bottom 6^a, as indicated in Fig. 2, and, as shown in said figure, an

outwardly-flaring side wall 14 is affixed upon 50 the seat-board 12.

It will be seen that the improved device for attaching the sides and ends of a vehicle-body upon the bottom frame thereof is entirely concealed from view, is very strong, is durable, and affords a neat finish for the vehicle-body; also, that the novel means for the attachment of the seat-frame to the body strengthens the sides of the latter and throws 55 the weight imposed upon the seat directly upon the frame 6 of the body.

Having thus fully described our invention, we claim as new and desire to secure by Letters Patent—

As an article of manufacture, a vehicle-body comprising a bottom, corner-posts, keys and side and end panels, all of said panels being mitered externally at the ends thereof, and provided with inner flat faces interrupted by keyways, said keyways extending entirely across said panels for the purpose of affording a firm grip throughout the entire width of said panels, the general location of the said keyways being obliquely opposite said mitered ends of said panels and parallel 75 with the inner faces of said panels, the mitered surfaces and said keyways being parallel with each other, the said corner-posts being provided with substantially V-shaped slots and with keyways, one wall of each slot 80 being interrupted by a keyway extending lengthwise of said post a distance representing the entire width of one of said panels, the said keys engaging with all of said keyways, the relative engagement of said mitered edges 85 and said keyways being such that each mutually locks the other throughout the entire length thereof, whereby each braces the other throughout the entire width of said panels.

In testimony whereof we have signed our 90 names to this specification in the presence of two subscribing witnesses.

JAMES E. BROWN.
CHAUNCEY B. BROWN.
